UNITED STATES PATENT OFFICE.

FRANK THORNTON, JR., OF MANSFIELD, OHIO, ASSIGNOR TO WESTINGHOUSE ELECTRIC & MANUFACTURING COMPANY, A CORPORATION OF PENNSYLVANIA.

SPOT-WELDING APPARATUS.

1,327,792.

Specification of Letters Patent. Patented Jan. 13, 1920.

Application filed April 18, 1919. Serial No. 290,941.

To all whom it may concern:

Be it known that I, FRANK THORNTON, Jr., a citizen of the United States, and a resident of Mansfield, in the county of Rich-
5 land and State of Ohio, have invented a new and useful Improvement in Spot-Welding Apparatus, of which the following is a specification.

My invention relates to apparatus for 10 spot welding and it has, for its primary object, the provision of apparatus of the above designated character which shall be relatively light in weight and compact of structure.

15 Another object of my invention is to provide spot-welding apparatus which shall permit of the employment of electric current to obtain both the necessary compressive force upon the objects being welded and 20 the heating effect to fuse the objects at the point where it is desired to unite them.

A still further object of my invention is to provide spot-welding apparatus which may be adjusted by skilled workmen and 25 thereafter operated, with a high degree of efficiency, by unskilled workmen.

With these and other objects in view, my invention will be more fully described, illustrated in the drawings, in the several views 30 of which corresponding numerals indicate like parts, and then particularly pointed out in the claims.

In the drawings, Figure 1 is a diagrammatic view of spot-welding apparatus and 35 electric control circuits therefor which embody my invention; Fig. 2 is a side view, on a larger scale, of a switch mechanism employed in the apparatus shown in Fig. 1, and Fig. 3 is a sectional view taken substantially along the line III—III of Fig. 2.

In practising my invention, I may employ apparatus, such as shown in Fig. 1, which comprises a base member 1 upon which may be secured, by any suitable means, such as 45 nuts and bolts 2, a plurality of supporting members 3 and 4, the supporting members being preferably insulated from each other, as indicated at 5. The member 3 may be provided, at one end, with a removable 50 clamping member 6 adapted to secure an electrode member 7 to the member 3. The other supporting member 4 may be provided with substantially parallel arms 8 so spaced as to permit of supporting an electrical coil 55 9 upon the lower arm. The electric coil 9

may be provided with an armature 10 which is preferably formed with a somewhat restricted portion 11 at its lower end which may function as an electrode and may also have another restricted portion 12 at its 60 other end. The armature 10 may be positioned within the coil 9 by disposing the electrode 11 in a suitable opening provided in the lower arm 8, and the restricted portion 12 may be extended through a similar 65 alined opening in the upper arm 8, the armature being held in its uppermost position by a spring 13 surrounding the end portion 12 and secured in such position by a nut 14.

A switch mechanism 15, which may be operated by the coil 9, by means of its armature 10, comprises a lever 16, carrying a switch blade 16', at one end, and may be connected, at its other end, to the upper end of the portion 12 of the armature 10 and may 70 be insulated therefrom. The lever 16 may be pivoted, as indicated at 17, and may be connected to a retarding device 18. A suitably supported resilient contact member 19 is adapted to coöperate with the switch 75 blade 16'.

The switch mechanism 15 is best shown in Figs. 1 and 2. The switch blade 16' may comprise a metallic plate 20 and a non-conducting plate 21 and may be mounted upon 85 the lever 16 at an angle thereto. Electrical contact is made between resilient member 19 and the metallic plate 20 when the switch blade 16' is moved upwardly, whereas downward movement of the blade, from a position above the member 19, will effect engagement between said member and the non-conducting plate 21.

The coil 9 may be connected across supply mains 22 by leads 23 and 24 which may be 95 provided with a suitable switch 25 for opening and closing the circuit of the coil 9. The amount of energy supplied to the coil 9 from the mains 22 may be regulated by a suitable rheostat 26. The switch blade 16' 100 and member 19 of the switch mechanism 15 may be connected in parallel with the coil 9 by a lead 27 which may be connected to the member 16' and to one side of the circuit, as indicated at 29, and by a lead 28 which 105 may be connected to the member 19 through a coil 30 of a relay switch 31 and to the other side of the coil circuit, as indicated at the junction point 31'.

A heating circuit may be provided by em- 110

ploying a transformer 32 having a primary winding 33, provided with voltage-control taps, which may be automatically connected in series with the supply mains 22 by the 5 relay switch 31 through contacts 34, 35, 36 and 37. A secondary winding 38 of the transformer 32 may be connected, at one side, to the supporting member 4 and at the other, to the supporting member 3, in 10 any suitable manner. A secondary circuit is thus provided which includes the electrode members 7 and 11, the electrode member 11 being connected to the supporting member 4 by a flexible lead 39.

15 In welding a plurality of metallic members together, the members may be disposed upon the stationary electrode member 7, and the circuit to the electric coil 9 may then be closed, through the switch 25, to energize 20 the coil 9, the degree of energy being regulated by the rheostat 26. When the coil 9 is energized, the armature is drawn into the coil, thus compressing the spring 13 and causing the electrode 11 to compressively 25 engage the members to be welded. The lever 16 is actuated by the movement of the armature 10 to cause the switch blade 16' to engage the resilient member 19. As before stated, electrical contact is made upon 30 the up-stroke of the switch blade 16', thereby closing a circuit through the coil 30 of the relay switch 31 which, therefore, automatically connects the primary winding 33 of the transformer 32 to the supply mains 35 22. In accordance with the well known transformer action, an electromotive force is induced in the secondary winding 38 of the transformer which causes a current to flow through the electrodes 7 and 11 and the 40 interposed work which coöperate to form a closed circuit.

The metallic members engaged by the electrodes are heated, on account of contact resistance, and the heated metal is united by 45 the compressive force produced by the electrodes. The degree of compression may be regulated, if desired, by adjusting the rheostat 26 which controls the energy supplied to the coil 9. Furthermore, the length of 50 time to which the members being welded are subjected to the heating effect of the current from the transformer may be varied by adjusting the retarding device 18 of the switch mechanism 15. The welding current 55 is supplied while the switch blade 16' is in contact with the resilient member 19 on its up-stroke, the circuit being broken when the switch blade 16' passes the resilient member 19. The lever arm 16 is held in its upper 60 position until the circuit energizing the

coil 9 is broken, the spring 13 being then permitted to raise the armature 10 and consequently to lower the lever arm 16.

Although I have described apparatus that is adapted for spot welding, it is obvious 65 that minor changes may be made in the construction thereof and in the electric control therefor, and I desire that no limitations shall be imposed except such as are indicated in the appended claims. 70

I claim as my invention:

1. A spot-welding apparatus comprising a plurality of electrode members, electro-magnetic means for forcing the members into engagement with interposed work, and 75 an automatically actuated circuit-closer for closing a heating circuit including the electrode members.

2. A spot-welding apparatus comprising a plurality of electrode members, electro-magnetic means for forcing the members into engagement with interposed work, means for automatically connecting the electrode members in a heating circuit, and means for automatically disconnecting the electrode 80 members from the heating circuit.

3. A spot-welding apparatus comprising a plurality of electrode members, electro-magnetic means for forcing the members into engagement with interposed work, 90 means for automatically connecting the electrode members in a heating circuit, and means for automatically disconnecting the electrode members from the heating circuit 95 at a predetermined time.

4. A spot-welding apparatus comprising a stationary and a movable electrode, an electric coil adapted to force the movable electrode toward the stationary electrode when it is energized, means for automatically connecting the electrodes in a heating 100 circuit, and means for automatically disconnecting the electrodes from the heating circuit at a predetermined time.

5. A spot-welding apparatus comprising 105 a stationary and a movable electrode, an electric coil adapted to force the movable electrode toward the stationary electrode when it is energized, means for varying the energy supplied to the coil, means tending 110 to maintain the electrodes in spaced relation, means for automatically connecting the electrodes in a heating circuit, and means for automatically disconnecting the electrodes from the circuit at a predetermined time. 115

In testimony whereof I have hereunto subscribed my name this 31st day of March, 1919.

FRANK THORNTON, Jr.
